(57) **CLAIM**

The ornamental design for a floating debris skimming device, as shown and described.

DESCRIPTION

FIG. 1 is a top perspective view of a floating debris skimming device showing our new design;

FIG. 2 is a bottom perspective view thereof;

FIG. 3 is a top view thereof;

FIG. 4 is a bottom view thereof;

FIG. 5 is a front view thereof;

FIG. 6 is a back view thereof; and,

FIG. 7 is a right side view thereof, the left side being a mirror image of the right side.
